UNITED STATES PATENT OFFICE.

GILBERT L. CROWELL, JR., OF ARLINGTON, NEW JERSEY, ASSIGNOR TO
DAMON GREENLEAF AND JOSEPH HAYDEN CROSBY, JR., BOTH OF
JACKSONVILLE, FLORIDA.

DESIGN FOR A SPOON OR SIMILAR ARTICLE.

SPECIFICATION forming part of Design No. 21,560, dated May 24, 1892.

Application filed April 13, 1892. Serial No. 429,070. Term of patent 7 years.

To all whom it may concern:

Be it known that I, GILBERT L. CROWELL, Jr., a citizen of the United States, and a resident of Arlington, in the county of Hudson 5 and State of New Jersey, have invented and produced a new, original, and useful Design for Handles of Spoons or Similar Articles, of which the following is a description, reference being made to the accompanying drawings, which fully illustrate the design as applied to a spoon-bowl.

In the drawings accompanying this description and representing the design as applied to a spoon-handle, Figure 1 is the front of the 15 handle of the spoon, and Fig. 2 represents the back side of the handle.

The essential feature of the design is the representation of an alligator surmounting a shank or stem composed of conventionalized 20 foliage. At the top of the handle is the rep-

resentation A of an alligator with body and tail in a winding vertical position and head and neck bowed from the vertical position to or nearly to the horizontal.

B represents the main portion, stem, or shank 25 of the handle. This is shown as in the form of curved and bent foliage composed of cultrate leaves bunched and progressively spreading or broadening to the position of the alligator, which latter is represented as grasping 30 and surmounting the handle or shank.

What is claimed as new is—

The design for handles of spoons or similar articles, substantially as herein shown and described.

GILBERT L. CROWELL, JR.
